UNITED STATES PATENT OFFICE

JOHN RESTO, OF NEW YORK, N. Y.

DESIGN FOR A CURTAIN TIE BACK OR SIMILAR ARTICLE

Application filed March 5, 1930. Serial No. 34,733. Term of patent 3½ years.

To all whom it may concern:

Be it known that I, JOHN RESTO, a citizen of Italy, residing in New York city, borough of the Bronx, in the county of Bronx and State of New York, have invented a certain new, original, and ornamental Design for Curtain Tie Backs or Similar Articles, of which the following is a specification, reference being had to the accompanying drawings, forming a part thereof, and of which Figure 1 is a plan view of the curtain tie back in open position, and Fig. 2 is a perspective view thereof mounted in position with a cur-

tain, window and fastener shown in dotted lines.

The design includes a conventionalized daisy having three leaves at right angles, and a band, there being a substantially uniform beading along the edges of the daisy petals, and leaves and the band, which beading forms loops as the ends of the band.

I claim:

The ornamental design for a curtain tie back or similar article substantially as shown and described.

JOHN RESTO.
